ROTARY CARD INDEX DRIVE
MECHANISMHerbert C. Behrens, Canton, Ohio, assignor to
Diebold, Incorporated, Canton, Ohio, a corpora-
tion of Ohio

Application October 20, 1948, Serial No. 55,583

6 Claims. (Cl. 312—305)

1

The invention relates generally to rotary card indexes of the type shown in the patent to G. C. Bruen, No. 2,168,323, dated August 8, 1939, in which record cards are arranged substantially radially of a mounting drum which is rotatable on a horizontal axis, and more particularly to an improved drive mechanism for rotating the drum.

In the operation of a rotary card index, groups or blocks of cards are often removed from the drum for convenience in working on individual cards or for dividing the work among several operators. When this is done the drum becomes unbalanced, and some means must be provided to keep the drum from turning due to the unbalanced load. A brake drum and band has been provided for this purpose, but in order to hold the drum in unbalanced position, the band has to be so tight that it is very difficult to turn the drum manually by gripping the ring of the usual hand wheel attached thereto.

It has been attempted to provide a worm drive between the hand wheel and drum, because a worm drive would be self-locking and thus remove the necessity for a brake, but an easily operated worm drive was found to be unsatisfactory because it produced a speed ratio between the wheel and drum of the order of 10-1, which was impractical as the drum turned too slowly when the hand wheel was turned.

Another difficulty encountered was that the size of the stand and housing for the drum were required to be kept at standard size and could not be increased to take care of an additional drive mechanism, nor could the size or capacity of the drum be reduced for that purpose.

It is an object of the present invention to provide a novel and improved drive mechanism for facilitating turning the drum of a rotary card index, especially when in unbalanced condition.

Another object is to provide an improved drive mechanism which is self-locking when the wheel is stopped either in balanced or unbalanced condition, thereby eliminating the need for a brake or additional locking means.

A further object is to provide an improved mechanism which produces an amount of speed reduction between the hand wheel and drum such as to enable turning the drum easily but not too slowly for practical purposes.

Another object is to provide an improved driving mechanism which is wholly supported on the drum shaft and drum shaft support.

Another object is to provide an improved drive mechanism which operatively connects the hand wheel and drum within the drum housing, without increasing the size of the housing or decreasing the size of the drum.

A further object is to provide an improved drive mechanism which enables a reduction in the size of the hand wheel.

2

A still further object is to provide a novel and improved drive mechanism which is easily applied to rotary card indexes of standard construction, and which is adapted for use with a manual or power driven rotary card index.

These and other objects are accomplished by the parts, constructions, arrangements and combinations which comprise the present invention, the nature of which is set forth in the following general statement, and a preferred embodiment of which is set forth in the following description and illustrated in the accompanying drawings, and which is particularly and distinctly pointed out and set forth in the appended claims forming part hereof.

In general terms, the drive mechanism comprising the present invention includes a worm wheel mounted on one end of the drum shaft which is rotatably supported on a stand within the card index housing, said worm wheel meshing with a worm on a shaft journaled in said stand, and an overdrive including a pinion on the worm shaft and a gear meshing with the pinion and journaled in the stand, the hand wheel being secured on the shaft of said gear.

Referring to the drawings forming part hereof in which a preferred embodiment is shown by way of example:

Figure 1 is a side elevation of a rotary card index embodying the present invention, the rotating hood for the drum being lowered in telescoped position within the housing, and parts of the housing and hood being broken away;

Fig. 2 is a fragmentary enlarged plan sectional view as on line 2—2, Fig. 1;

Fig. 3 is a transverse sectional view of the rotary card index shown in Fig. 1, on a slightly enlarged scale, the hood being shown in raised position;

Fig. 4 is an enlarged fragmentary sectional view as on line 4—4, Fig. 3;

Fig. 5 is a fragmentary plan elevational view thereof; and

Fig. 6 is a fragmentary sectional view as on line 6—6, Fig. 4.

Similar numerals refer to similar parts throughout the several views of the drawings.

The rotary drum indicated generally at 6 in Fig. 2, and in dot-dash outline in Fig. 3, is preferably similar to the drum shown in the patent to K. H. Miller No. 2,389,923, dated November 27, 1945. The drum 6 has a peripheral wall 7 on which rail segments 8 are detachably mounted, and a follower member indicated generally at 9 is slidably mounted on each detachable rail segment for adjustably supporting a group or block of cards 10 detachably mounted on each rail segment.

The drum 6 is mounted in a usual fashion on a horizontal shaft 11, and the reduced ends 12 of

the shaft are journaled by means of needle or roller bearings 13 in a stand consisting of upwardly extending plates 14 and 15 having angular flanges 16 and 17 respectively at their bottom ends. The angular flanges 16 and 17 are secured to a base 18 by screws 19, and the base 18 is rollably supported on the floor in a usual manner by means of rollers 20 and 21.

The housing for the drum may consist of side plates 22, which are secured as by welding to a pair of vertical side bars 23 mounted on the base by means of angle brackets 24, and U-shaped end plates 25 secured at their ends to the side plates 22 and supported on the base by angle brackets 26. Preferably, the upper edges of the side plates 22 and end plates 25 have inturned rims as indicated at 27 in Fig. 3. As shown, the top portion 14' of plate 14 is offset inwardly of the housing to provide additional space between the housing and drum for mounting the novel driving mechanism which rotates the drum.

A sheet metal hood indicated at 28 is rotatably telescoped within the housing, as shown in Fig. 1, for being rotated to cover the drum 6 and the hand wheel 29 when the hood is in raised position as indicated in Fig. 3. The side plates 30 of the hood are preferably secured as by welding to substantially triangular rub plates 31, and the rub plates are secured as by screws 32 to counterweight plates 33 which are journaled at 34 on the vertical side bars 23. The counterweight plates 33 are designed to aid in raising the hood to the closed position in Fig. 3. As shown in Fig. 1 the plates 14 and 15 are offset longitudinally of the housing to compensate for the offset load of the counterweight plates 33.

The rotary card index thus far described is of more or less conventional construction and per se forms no part of the present invention.

As shown in Fig. 3, the end of the drum shaft 11 which is journaled in the support plate 14 has a reduced portion 35 projecting outwardly beyond the plate 14, and a worm gear or wheel 36 is secured on said reduced portion. The worm gear 36 meshes with a worm 37, which preferably is a double pitch four-thread worm, and the worm 37 is secured by a key 37' on a shaft 38 which extends transversely of the drum shaft 11. The ends of the worm shaft 38 are journaled preferably by means of needle bearings 39 in mounting bars 40 which are carried on triangular bracket plates 41 welded to the top of support plate 14. Preferably, the bars 40 are connected together by means of transverse web plates 42 and 43 which are welded at their ends to the bars.

One end of the worm gear projects beyond one of the bars 40 and has a bevel pinion 44 secured thereon by means of a tapered pin 45, and the other end is provided with anti-friction thrust bearings 46 on each side of the bar 40, the outer bearing 46 being held on the shaft by means of a thrust collar 47 and stud screw 48, and the inner bearing 46 being held in place by abutment with a thrust bushing 49 abutting the worm 37 at its other end.

The bevel pinion 44 meshes with a bevel gear 50 which is mounted on a stub shaft 51 by means of a bushing 52. The inner end of the shaft 51 has a retaining flange 53 thereon which engages the web plate 43 and the outer end of the shaft 51 has a thrust washer 54 secured thereto by a stud 55. Preferably, the inner end of stub shaft 51 is journaled in an anti-friction bearing 56 mounted in the web plate 43, and the intermediate portion of the shaft 51 is journaled in an anti-

friction bearing 57 which is mounted in a circular boss 58 projecting outwardly from the web plate 43.

The hand wheel 29 for manually rotating the drum is provided with spokes 59 which are threaded into the hub 60 of the beveled gear 50, as shown in Fig. 3, so that the hub 60 acts as the hub of the hand wheel. Preferably, the tubular ring 29 of the hand wheel is made of a plastic material.

Thus, the hand wheel 29 and all of the driving mechanism between the hand wheel and the worm wheel 36 are mounted directly on the support plate 14 which carries one end of the drum shaft 11. Moreover, by offsetting the support plate 14 inwardly of the drum shaft, the driving mechanism is mounted between the hand wheel and drum shaft, without increasing the width of the housing for standard size rotary card indexes, and without necessitating any decrease in the width or capacity of the drum 6 rotatably mounted within the housing.

In the operation of the rotary card index embodying the novel drive mechanism, when the hood 28 is revolved to open position, the drum is turned by manually turning the hand wheel 29, and when the wheel is stopped, the driving connection between the worm 37 and worm wheel 36 is self-locking so as to hold the drum in position, even though one or more blocks of cards are removed so as to unbalance the drum. The worm 37 and worm gear 36 are designed to produce a speed ratio of about 10 to 1 in order to provide for easy rotation of the drum by rotating the hand wheel.

However, with such a ratio, the speed of the drum is so slow as to be impractical, because ten revolutions of the hand wheel are required to produce one revolution of the drum. By providing the bevel gear overdrive consisting of the bevel gear 50 and bevel pinion 44 with a ratio of about 4 to 1, the net speed ratio between the hand wheel and the drum is only about 2½ to 1, which is very satisfactory for all practical purposes in the operation of the rotary card index.

Moreover, by combining the bevel gear overdrive with the worm drive, the rotation of the drum is made sufficiently easy so that the size of the hand wheel 29 can be substantially reduced and requires less vertical space within the housing of the rotary card index, so as not to extend above the cards 10 carried on the drum 6, even though the axis of the hand wheel 29 is offset upwardly from shaft 11.

The novel and improved drive mechanism is simple and inexpensive, and easily applied to rotary card indexes of standard size and construction. Furthermore, the novel drive mechanism is easily adapted to a motor drive instead of a manual drive by operatively connecting the motor directly to the bevel gear 50. The novel drive enables easily turning the drum either balanced or unbalanced condition, and provides self-locking means for locking the drum at any position, without requiring additional brake means.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is

by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driving mechanism for rotating the drum including a worm gear on the projecting end of said shaft, a worm shaft journaled on said offset support member transversely of said drum shaft and inwardly of the lateral edge of the drum, a worm on said worm shaft meshing with said worm gear, a bevel pinion on said worm shaft, a bevel gear journaled on said offset support member and meshing with said pinion, and means for driving said bevel gear.

2. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driving mechanism for rotating the drum including a worm gear on the projecting end of said shaft, a worm shaft journaled on said offset support member transversely of said drum shaft and inwardly of the lateral edge of the drum, a worm on said worm shaft meshing with said worm gear, a bevel pinion on said worm shaft, a bevel gear journaled on said offset support member on an axis offset laterally of said drum shaft and meshing with said pinion, and a hand wheel mounted coaxially on said bevel gear and located within the housing alongside the drum.

3. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driving mechanism for rotating the drum including a worm gear on the projecting end of said shaft, a pair of mounting bars secured on said offset support member and spaced laterally of said drum shaft and inwardly of the lateral edge of the drum, a worm shaft journaled in said mounting bars transversely of said drum shaft, a worm on said worm shaft meshing with said worm gear, a bevel pinion on said worm shaft, a web plate connecting said mounting bars, a bevel gear journaled on said web plate and meshing with said pinion, and means for driving said bevel gear.

4. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driv-

ing mechanism for rotating the drum including a worm gear on the projecting end of said shaft, a pair of mounting bars secured on said offset support member and spaced laterally of said drum shaft and inwardly of the lateral edge of the drum, a worm shaft journaled in said mounting bars transversely of said drum shaft, a worm on said worm shaft meshing with said worm gear, a bevel pinion on said worm shaft, a web plate connecting said mounting bars, a bevel gear journaled on said web plate on an axis offset laterally of said drum shaft and meshing with said pinion, and a hand wheel mounted coaxially on said bevel gear and located within the housing alongside the drum.

5. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driving mechanism for rotating the drum including a worm gear on the projecting end of said shaft, a pair of laterally spaced mounting bars secured on said offset support member inwardly of the lateral edge of the drum and projecting outwardly therefrom, a worm shaft journaled in said mounting bars and extending transversely above said worm gear, a worm on said worm shaft meshing with said worm gear, a bevel pinion on said worm shaft, a transverse web plate connecting the projecting ends of said mounting bars, a bevel gear journaled on said web plate between said mounting bars and meshing with said pinion, and means for driving said bevel gear.

6. In a rotary card index including a housing, a stand within the housing, a rotatable drum having a shaft journaled in the stand; said stand including a support member at one side of the drum and offset inwardly of the drum shaft for engaging the shaft at a point spaced inwardly from one lateral edge of the drum, driving mechanism for rotating the drum including a worm gear on the projecting end of said shaft, a pair of laterally spaced mounting bars secured on said offset support member inwardly of the lateral edge of the drum and projecting outwardly therefrom, a worm shaft journaled in said mounting bars and extending transversely above said worm gear, a worm on said worm shaft meshing with said worm gear, a bevel pinion on said worm shaft, a transverse web plate connecting the projecting ends of said mounting bars, a bevel gear journaled on said web plate between said mounting bars on an axis offset laterally of said drum shaft and meshing with said pinion, and a hand wheel mounted coaxially on said bevel gear and located within the housing alongside the drum.

HERBERT C. BEHRENS.
